UNITED STATES PATENT OFFICE

159,090

COMBINED LIPSTICK AND CONTAINER

Helen Neuschaefer, Rye, N. Y., assignor to A. Sartorius & Co., Inc., New York, N. Y., a corporation of New York

Application November 20, 1947, Serial No. 142,699

Term of patent 14 years

(Cl. D86—10)

To all whom it may concern:

Be it known that I, Helen Neuschaefer, a citizen of the United States, residing at Rye, New York, in the county of Westchester and State of New York, have invented a new, original, and ornamental Design for a Combined Lipstick and Container, of which the following is a specification, reference being had to the accompanying drawing, forming part thereof.

Fig. 2 is a top plan view thereof; and

Fig. 3 is a side view thereof in open position.

The cover tip in each of the three drawing figures and the lipstick in Fig. 3 are lined vertically to indicate the color red.

The back of the lipstick container is substantially like the front shown in Fig. 1.

I claim:

The ornamental design for a combined lipstick and container, as shown and described.

HELEN NEUSCHAEFER.
